UNITED STATES PATENT OFFICE.

FREDRICK H. WENDT, OF ERIE, PENNSYLVANIA, ASSIGNOR TO THE BROWN FOLDING MACHINE COMPANY, OF SAME PLACE.

FOLDING-MACHINE.

SPECIFICATION forming part of Letters Patent No. 615,770, dated December 13, 1898.

Application filed June 29, 1897. Serial No. 642,863. (No model.)

To all whom it may concern:

Be it known that I, FREDRICK H. WENDT, a citizen of the United States, residing at Erie, in the county of Erie and State of Pennsylvania, have invented certain new and useful Improvements in Folding-Machines; and I do hereby declare the following to be a full, clear, and exact description of the invention, such as will enable others skilled in the art to which it appertains to make and use the same.

This invention relates to double-folding machines; and it consists in certain improvements in the construction thereof, as will be hereinafter fully described, and pointed out in the claims.

The invention is illustrated in the accompanying drawings, as follows:

Figure 1 shows a section on the line 1 1 in Figs. 2 and 3. Fig. 2 shows a plan view, the top (not shown) being removed to better show construction. Fig. 3 shows a section on the line 3 3 in Figs. 1 and 2, a part being broken away to a section on the line 3' 3' in said figures.

25 A marks the sides of the frame, and A' the cross-pieces of the frame. The first-fold rolls comprise the roll B, of ordinary construction, and a companion roll formed of the longitudinally-movable members B' B' and fixed roll B², all arranged on a shaft B³. The movable rolls B' B' are provided with a spline b² and groove mechanism, which locks them against rotation on the shaft B³ and allows their free longitudinal movement on said shaft. The 30 rolls are provided with the gears B⁴ B⁴, one on the shaft B³ and the other on the roll B, to compel them to move in unison. A drive-shaft F is journaled in the frame under the folding-roll B. A drive-pulley F' is mounted 35 on this shaft, and a gear F² meshes a gear B⁵ on the shaft carrying the roll B, so that the roll B is driven from the shaft F.

The roll B² is provided with an annular groove b', into which runs a slitter-roll c, which 40 is mounted on the shaft C. The shaft C is journaled in the frame and a bracket C² secured to one of the cross-pieces. It has a gear C', which meshes a gear B⁴ and causes the rotation of the shaft C.

45 As the paper passes through the first-fold

rolls it is deflected, as commonly, by tapes, (not shown,) which start and carry the paper through the slitter and over the second-fold rolls D D, one set at each side of the machine. The slitter having separated the paper, the 55 duplicate folding mechanisms at each side of the machine each take a sheet and fold it independently of the duplicate mechanism at the opposite side of the machine. The shaft D⁸ of one of each pair of rolls D has mounted 60 on its end a gear D³, which meshes a gear f on the shaft F. The gear f has a grooved hub and is secured to the shaft F by a spline and groove mechanism, so that it is locked against rotation on the shaft, but is free to move longitudinally thereon. Each mechanism is provided with the usual starter D'. This starter is carried by the arms D⁴ D⁴, which are carried by a shaft D⁵, mounted in the frame. An arm L⁶ extends from the shaft D⁵ and is provided at its end with a roller D⁷. A shaft G is journaled in the frame and has mounted upon it two cams G' of considerable length. The roller D⁷ is arranged to ride the cam G', and the cam is so shaped as to give to the 75 starter D' the desired starting movement. A gear G² on the end of the shaft G meshes with a gear F⁸ on the shaft F, by means of which the shaft G is driven.

In order that different sizes of sheets may 80 be folded through their center at the second fold, the second-fold rolls D D, with their starters D', are mounted in sliding boxes D², which allows these rolls, with attendant mechanism, to be shifted to and from the center of 85 the machine, as the size of the sheet requires. The cams G' are sufficiently long to present a cam-surface to the roller D⁷ in all positions.

The sliding boxes are arranged on the cross-pieces A' in guides a a, and the boxes extend through slots a' in the cross-pieces and are provided with the racks d on their lower edges. Gears d', carried by the shafts d², mesh the racks d. The shafts d² are journaled on the frame and are operated by means of a hand-wheel d³.

The paper passing from the second-fold rolls is deflected by tapes, (not shown,) as commonly, and is carried over the third-fold 100

rolls E E, through which it is run. There may be subsequent folds, if desired. The rolls E E are journaled in cross-pieces E'.

In order that wrinkling at the third fold may be prevented, I pass the sheet through a perforator before passing it through the second-fold rolls. The perforator consists of the perforating-wheel c', mounted on a sleeve c². The sleeve has the annular groove c³ and is mounted on the shaft C and locked against rotative movement thereon by the spline c⁴. It is free to move longitudinally on the shaft C, however. A bracket d⁶, having the fork d⁷, which engages the grooved sleeve c², is attached to and carried with the sliding box D². The perforating-wheel c' is therefore moved with the rolls D D, so that it is always in register with the folding-line of the rolls. This brings the perforated line on the sheet at the fold as desired and provides for the perforation of different sizes of sheets. The bracket d⁶ is also provided with a fork d⁸, which engages the grooved hub of the gear f. This mechanism moves the gear f, with the sliding boxes, so that it is kept in mesh with the gear D³.

The roll B' is provided with the annular groove b, into which the perforating-wheel c' runs. In order that this groove may be kept in register with the perforating-wheel in its various positions, a bracket d⁴, attached to the sliding box D², is provided, and this bracket has a forked end d⁵, which engages the roll B' by means of a groove b³, so that the roll B' is moved with the sliding box D² and the perforating-wheel.

If desired, the sheets may be passed through the first-fold rolls without making a fold. In this case what I term the "second" fold 40 will, in reality, be the first fold. The perforation would in this case also be effective for the object sought, but not so necessary.

What I claim as new is—

1. In a folding-machine, the combination 45 with a set of adjustable folding-rolls; of a perforator; and means for automatically adjusting said perforator with each adjustment of said folding-rolls to maintain it in register with the folding-line of said rolls.

50 2. In a folding-machine, the combination with the folding-rolls D D; of the sliding boxes carrying said rolls; a shaft C; a perforating-wheel mounted on said shaft and arranged to be movable longitudinally thereon;

and means carried by said sliding box for 55 moving said perforating-wheel longitudinally on the shaft.

3. In a folding-machine, the combination with the folding-rolls D D; of the sliding boxes carrying said rolls; a shaft C; a perforating-wheel mounted on said shaft and arranged to be movable longitudinally thereon; means carried by said sliding box for moving said perforating-wheel longitudinally on the shaft; a shaft B³; a roll B' mounted on 60 said shaft B³ and arranged to be movable longitudinally thereon; and being provided with an annular groove b in which the perforator runs; and means carried by said sliding box for moving said roll longitudinally with the 70 perforating-wheel.

4. In a double-folding machine, the combination with a centrally-located slitter; two sets of folding-rolls, one each side of the slitter and adjustable to and from the slitter; of 75 a perforator for each set of folding-rolls; and means for automatically adjusting said perforators with each adjustment of said folding-rolls to maintain them in register with the folding-line of said rolls. 80

5. In a double-folding machine, the combination with two sets of folding-rolls oppositely placed; and sliding boxes carrying said rolls which are adjustable to and from each other; of a shaft C; slitter c mounted on said 85 shaft; longitudinally-movable perforating-wheels c' also mounted thereon; and means for moving said perforating-wheels with said sliding boxes.

6. In a double-folding machine, the combination with two sets of folding-rolls oppositely placed; and sliding boxes carrying said rolls which are adjustable to and from each other; of a shaft C; longitudinally-movable perforating-wheels c' mounted on said shaft; 95 means for moving said perforating-wheels with said sliding boxes; a shaft B; longitudinally-movable rolls B' on said shaft provided with the annular grooves b in which run the perforating-wheels; and means for moving said rolls B' with the said sliding boxes. 100

In testimony whereof I affix my signature in presence of two witnesses.

FREDRICK H. WENDT.
